UNITED STATES PATENT OFFICE.

DAVID BLACK, OF TOLEDO, OHIO, ASSIGNOR OF THREE-FOURTHS TO ISAAC N. HUMPHREY AND JOHN T. GREER, BOTH OF SAME PLACE.

VELOCIPEDÉ.

SPECIFICATION forming part of Letters Patent No. 350,719, dated October 12, 1886.

Application filed February 25, 1886. Serial No. 193,151. (No model.)

To all whom it may concern:

Be it known that I, DAVID BLACK, of Toledo, in the county of Lucas and State of Ohio, have invented new and useful Improvements in 5 Tricycles; and I do hereby declare that the following is a full, clear, and exact description thereof, reference being had to the accompanying drawings, which form a part of this specification.

10 This invention relates to certain new and useful improvements in tricycles; and the invention consists in the peculiar construction and arrangement of the frame, the seat-supports, the propelling-gear, and the brake and 15 steering apparatus, all as more fully herein-after shown and described.

In the drawings which accompany this specification, Figure 1 is a perspective view 20 of my improved tricycle, with the large wheels only shown in dotted outlines. Fig. 2 is a detached perspective of the manner in which the motion is conveyed to the drive-wheels, and Fig. 3 is a sectional perspective of the hub of 25 one of the drive-wheels. Fig. 4 is a sectional perspective of one end of the axle. Fig. 5 is a side view of the steering and brake apparatus.

The frame-work of this machine consists of 30 tubular bars connected together by suitable couplings, as shown, to form a continuous rail running around the front and upon the two sides. The rear ends of the side rails, A, form 35 upward return-bends B terminating in vertical standards, C, which are secured at their lower ends to the side rails. The return-bends B are connected by a cross-bar, D, which thus forms the rear side of the frame.

E is the rear axle, upon which the two large 40 drive-wheels are journaled, and which is provided with two cranks, F F, formed upon the opposite sides thereof. The axle E revolves in suitable bearings, G, which are clipped to the side rails, as shown.

The seat H (shown in dotted outline) is supported upon a double - curved bar or leaf spring, I, placed longitudinally in the center 45 between and above the side rails. The central portion of said spring between the curved portions forms a saddle, a, by means of which the spring is secured to and suspended on a cross-bar, J. The latter is sleeved with its ends upon the standards C, with coil-springs K

placed underneath and adjustably supported by set-collars L.

M M are the pedals which actuate the pedal-levers, each of which consists of two members, 55 N O, hinged together at or near the center by a knuckle-joint. The members O of each pedal-lever are journaled with their front ends upon the front rail at b. The other members, N, are bent outwardly at i, and their rear ends 60 are journaled unto the crank of the axle. The inner ends of the members of each lever are bifurcated, and a bolt, c, hinges the bifurcated ends together and serves as a pivot upon which the pedals turn.

P is the guiding-wheel. It runs in advance 65 of the crank-axle upon a short axle secured in the lower ends of a forked standard, Q, which turns on a vertical pivot pin in the cross-coupling R of the frame.

The steering lever S is secured by means of 70 a vertical hinge joint to the end of the pivot-pin, so that it may be reversed and used to draw the machine when necessary, as in the case of steep hills.

T is a brake-shoe for the guiding-wheel. It is secured to the end of a brake-lever, d, which passes through the fork of the standard directly over the wheel, and is fulcrumed at e. The upper end of the brake-lever is connected 80 by a wire, f, which runs along the steering-lever, with a little hand-lever, g, placed in convenient proximity to the handle h of the steering-lever. A spring, i, is arranged to keep the brake shoe normally out of contact with 85 the wheel.

U are two small steel ratchet-wheels secured 90 near the inner end of the spindles V of the axle, and W are steel ratchet-dogs or clicks secured upon the inner and recessed face of 95 the hubs of the large wheels, and adapted to operate in connection with the ratchets to transmit a forward motion to the wheels. This arrangement of ratchets and dogs permits each wheel to run ahead of its motion independently of the other in turning.

The wheels are what are termed "spider-wheels," and are tired with rubber. A step may be fixed to one side for mounting and dismounting, and the cross-bar D, back of the 100 seat, may be arranged to carry a suitable amount of baggage.

By constructing the pedal-levers and the seat in the manner described all complication in the construction of the frame is avoided, while at the same time all the stress is brought directly onto the frame itself, which, owing to its shape and construction, is very rigid.

It will be observed that the cranks are placed near the bearings of the axle, and that portion of the axle between the cranks is straight, so as to act as a brace, and in order to bring the pedals in proper proximity to each other the pedals are bent, as shown at *i*. This construction prevents the strain on the axle from acting injuriously.

15 What I claim as my invention is—

1. In a tricycle, a pedal-movement consisting of bifurcated pedal-levers provided with knuckle-joints at or near their center, which form the pivots for the pedals, which pedals 20 work between the bifurcations of said levers, said pedal-levers being journaled at one end to the cranks and at the other to the frame, substantially as described.

2. In a tricycle, the combination of the frame 25 forming a continuous front and side rail, of the double throw crank-axle journaled in bearings clipped to the side rails, and having the cranks formed near said bearings and connected by a straight portion of the axle, of the 30 pedal-levers provided with knuckle-joints and journaled at one end to the cranks and at the other to the frame, and of the bends *i* in said pedal-levers, all arranged substantially as and for the purposes described.

35 3. In a tricycle, a supporting-frame forming a continuous rail on the front and sides, and provided with upward return-bends terminat-

ing in vertical standards, which are secured to the side rails, combined with the cross-bar *J*, sliding on said standards, and the springs *R* on said standards beneath said cross-bars, substantially as specified.

4. In a tricycle, the combination of a supporting-frame forming a continuous rail in front and on the sides, and having an upward return-bend terminating in vertical standards *C*, in combination with the cross-bar *J*, guided upon said standards, substantially as described.

5. In a tricycle, the combination of a supporting-frame consisting of a continuous rail forming the side rails and front rail, of the cross-coupling *R* in the front rail, of the bar *D*, connecting the return-bends *B*, and of the double-throw crank-axle *E*, running in bearings *G*, clipped to the side rails, and extended parallel 55 with said side rails, as shown, to bring the cranks in proximity to said rails, all arranged substantially as described.

6. In a tricycle, in combination, the standards *C*, the cross-bar *J*, the coil-springs *K*, the 60 double-curved spring-bar *I*, saddled upon the cross-bar *J*, and the seat *H*, all arranged substantially as described.

7. In a tricycle, in combination, the seat *H*, the double-curved spring-bar *I*, saddled upon 65 the cross-bar *J*, the cross-bar *J*, the coil-springs *K*, the set-collar *L*, and the standard *C* of the frame, all arranged substantially as described.

DAVID BLACK.
